UNITED STATES PATENT OFFICE.

CLARENCE H. POST, OF SEATTLE, WASHINGTON.

CARTON.

1,259,666.

Specification of Letters Patent. Patented Mar. 19, 1918.

Application filed January 13, 1917. Serial No. 142,212.

To all whom it may concern:

Be it known that I, CLARENCE H. Post, of Seattle, in the county of King and the State of Washington, have invented certain new and useful Improvements in Cartons; and I do hereby declare that the following is a full, clear, and exact description of the invention, such as will enable others skilled in the art to which it appertains to make and 10 use the same.

The present invention relates to improvements in cartons or similar receptacles and particularly to the knock-down type of boxes, such for instance as are much used in 15 packing and transporting certain kinds of goods where light, inexpensive, yet reasonably strong closures are required and one which will protect the contents from breakage.

20 It is an object of the present invention to provide a carton of the character set forth which when folded will interlock itself without any additional fastening means such as stitches and staples.

25 A further object of the invention is to provide a suitable cell forming filler which when placed within the carton will assist the latter to be retained in its folded position.

With the above and other objects in view 30 which will hereinafter appear as the description continues, the invention consists of the novel features of construction, combination and formation of parts as will be hereinafter more fully described and particularly pointed out in the appended claim.

In the accompanying drawings has been shown the simple and preferred form of the invention, it being, however, understood that no limitation is necessarily made to the precise structural details herein exhibited, but the right is hereby reserved to any changes, 40 alterations or modifications to which recourse may be had that come within the scope of the invention without departing 45 from the spirit thereof or sacrificing the efficiency of the same.

In the accompanying drawings:

Figure 1 is a vertical transverse section through the carton when in its folded position showing the cellular filler arranged therein;

Fig. 2 is a horizontal section of the same;

Fig. 3 is an end elevation;

Fig. 4 is a vertical transverse sectional view;

Fig. 5 is a plan view of a blank being so

shaped as to produce when folded the carton of the present invention;

Fig. 6 is a plan view of a slightly modified form of one of the fillers; 60

Fig. 7 is a plan view of another slightly modified form of the filler; and,

Fig. 8 is a vertical section through the same taken on the line 8—8 of Fig. 7 in the direction of the arrows. 65

The carton forming the subject matter of the present invention is designed to afford an improved receptacle or closure of the folding type which is particularly adapted for the packing and transportation of goods 70 which are best mounted or inclosed in a cellular structure.

The invention is particularly suited to the packing of eggs or other articles liable to breakage, as for instance electric light bulbs, 75 fragile ornaments or the like.

In the accompanying drawings is illustrated a practical embodiment of the invention, the carton shown being especially well adapted for the reception of eggs and the 80 invention will now be described by having reference to the accompanying drawings wherein like and corresponding parts are designated throughout the several views by similar reference characters. 85

In Fig. 5 there is shown a blank cut from wood from the Pacific coast spruce which is odorless and tasteless although it can be made from other woods. This piece of veneer is of a rectangular configuration being 90 scored in a transverse direction across the grain so that it can be bent on the scores to form the carton. By bending this strip of veneer on the scores an end section 1 is provided which is to form the center partition of the carton and the outer edge thereof is provided with a plurality of notches 2. The adjacent section 3 is bent at right angles to form the bottom of one row of cells adapted to be formed within the receptacle. Bent 100 at right angles to the section 3 and adapted to extend parallel to the partition 1 is a section 4 and the adjacent section 5 is adapted to overlap the section 4 as better shown in Figs. 3 and 4 to form the front wall of the 105 carton. The section 6 forms the bottom of the carton whereas the section 7 forms the rear wall and the section 8 forms the top for the carton. The opposite end section 9 is adapted to form the interlocking flap which 110 is adapted to be inserted within the box and the front of the wall 4. This wall 4 is pro-

vided with a pair of elongated slots 10 which are for the reception of the flaps 11 formed within the section 9. By providing the slots 10 and the flaps 11 it will at once be conceived that this was a locking means for retaining the carton in its folded position or this looks as if it would strengthen the carton, but it is detrimental as it weakens the veneer and is used only as an illustration 10 how the cover may be locked in closed position.

The filler as shown in Figs. 1 to 4 inclusive of the drawings for this carton makes a cellular structure and end closures for the carton. In the drawings I have illustrated the 15 filler comprising two sections A and B for providing a carton for holding one dozen eggs, but, of course, it is to be understood that any number of fillers may be inserted 20 as cells are required. Each section of the filler comprises a continuous strip of veneer being bent so that the end sections 12 and 13 form the inner partitions and the adjacent side partitions 14 are connected thereto. 25 The ends of each filler section are provided with the walls or sections 15 which are connected at one end to the side partitions 14 and their opposite ends are connected by means of the single opposite side section 16. 30 The lower edges of the sections 12, 13 and 15 are notched as at 17 so as to be interlocked with the notches 2 formed within the central longitudinal partition 1. The front wall of the carton when folded has a tendency to 35 swing outwardly when the filler is not placed in position thereby leaving a slight space between the sections 4 and 5 but the weight of the eggs resting upon the section 3 will have a tendency to pull the sections 4 and 5 inwardly so that they will be held in substantially a vertical position.

When the filler is placed within the carton it will provide a locking means for retaining the same more securely in a folded position 45 and it is to be noted that the carton together with its filler comprise only three sheets of

veneer and does not need any stitches, staples or other fastening elements for retaining the same in folded position.

In Fig. 6 of the drawings the extreme 50 outer ends of the sections 12' and 13' of the filler are bent inwardly as at 17 and rest against the side section 16' so as to form a locking connection. In the modified form 55 of the filler as shown in Figs. 7 and 8 the extremities of the sections 12' and 13' are bent toward the opposite sections to which they are connected and the extremities are notched so as to form an interlocking connection. The extremity 18 is notched within 60 its lower edge as at 19 whereas the extremity 20 of the section 13' is notched within its upper edge for receiving the notch within the extremity 18 for forming this interlocking connection. 65

Having thus fully described my invention, what I claim as new and desire to secure by Letters Patent is:

A collapsible carton comprising a single sheet of veneer being scored to form a plurality of sections, one of the end sections being bent in a vertical position and notched, the adjacent section to said end section forming a portion of the bottom of the carton, the two next adjacent sections forming the 75 front wall of the carton, the remaining sections forming the bottom, rear wall and top of the carton and a locking section, the front wall of the carton adapted to be retained in vertical position when weight is applied 80 within the carton upon said section forming a portion of the bottom of the carton, said cover adapted to be held in locking engagement with said front wall by said locking section and a cell forming filler adapted to 85 interlock with the notches in said vertical end section when placed within the carton substantially as and for the purpose specified.

In witness whereof I have hereunto set my 90 hand.

CLARENCE H. POST.
